FLOATINGLY MOUNTED PERFORATING APPARATUS

Jerome L. De Boo, Chicago, Ill., assignor to Teletype Corporation, Chicago, Ill., a corporation of Delaware

Original application March 18, 1948, Serial No. 15,592, now Patent No. 2,545,198, dated March 13, 1951. Divided and this application January 4, 1949, Serial No. 69,229

11 Claims. (Cl. 164—89)

1

This invention pertains to perforating apparatus and more particularly to high speed telegraph tape reperforators.

This application is a division of copending application Serial No. 15,592, filed March 18, 1948 now Patent No. 2,545,198.

The principal object of this invention is to provide a perforating apparatus wherein the material being perforated may be advanced during the punching cycle.

For some time it has been sought to obtain a simplified telegraph tape reperforator in an effort to reduce the manufacturing costs. The reperforators in common use at the present time include a punch and die unit which requires very close tolerances in its manufacture, and consequently manufacturing costs are high. It is, therefore, another object of this invention to provide a reperforator wherein greater tolerances are allowable in the punch and die unit, thus reducing the cost of manufacture.

By this invention a high speed selector mechanism controls the selection of a plurality of punches in accordance with signals received by the selector mechanism. In the preferred embodiment of the invention the punches are floatingly mounted in slots in a stationary punch block. When the punches are selected in accordance with the signals received by the selector mechanism, the selected punches are caused to perforate a telegraph tape. Thereafter the tape is advanced simultaneously as the punches are withdrawn from the tape, which causes the punches to be moved pivotally until they are withdrawn from the tape.

Therefore, another object of the invention is to combine a high speed tape perforating mechanism with a high speed selector mechanism.

Still another object of the invention is to provide a reperforator having pivoted floating punches whereby the punches may move with the advancing tape.

In a modified form of the invention the punch block is mounted pivotally in order that it can be moved as the punches are advanced towards the tape during the perforating operation. By this form of the invention, the tape is advanced during the perforating movement of the punches, as well as while the punches are being withdrawn from the tape. Thus it is possible to increase the speed of the perforating operation since it is unnecessary that there be separate punching and tape feeding operations.

Therefore, a further object of the invention is to provide a reperforator wherein both the

2

punches and the die are pivoted in order that they may move with the advancing tape.

A still further object of the invention is to provide a manually operated backspace mechanism in a reperforator having a pivoted punch and die unit.

Other objects and advantages not specifically recited above will be apparent and the invention will be better understood by reference to the following detailed description when considered in conjunction with the accompanying drawings, wherein:

Fig. 1 is a fragmentary isometric view showing the principal features of the preferred embodiment of the invention;

Fig. 2 is a front elevational view of the reperforator with the front portion of the supporting frame removed for a better view of the features of the invention;

Fig. 3 is a detail fragmentary isometric view of the selector magnet and armature and the armature locking mechanism;

Fig. 4 is a detail isometric view of the punches;

Fig. 5 is a transverse view of a section of tape perforated by punches of the type shown in Fig. 4;

Fig. 6 is a front elevational view of a modified form of the invention showing permissively actuated punch interponents and a pivoted punch block;

Fig. 7 is a fragmentary isometric view of the tape feed and backspace mechanism used in the modified form of the invention shown in Fig. 6;

Fig. 8 is a side elevational view of the pivoted punch block and backspace mechanism shown in Fig. 7;

Fig. 9 is a timing diagram of the various operations of the preferred embodiment of the invention;

Fig. 10 is a view of several differently shaped punches suitable for use with the invention; and

Figs. 11, 12, 13, and 14 show various types of punch and die wheels for rolling in the feed holes in a telegraph tape.

This invention incorporates a high speed selector mechanism of the type disclosed in the patent to W. J. Zenner, No. 2,339,813, issued January 18, 1944. In the invention herein described a series of selector levers move to a permutation of marking and spacing positions depending upon the signals received by a selector magnet. When any of the selector levers move into marking position, cooperating selector interponents also move into marking position. Subsequent rotation of the selector cams causes both the selector levers and selector interponents to be moved to positions

to set a corresponding group of punch interponents. Thereafter the selector levers and selector interponents return to normal position, thus providing for overlap. A punch bail engages and moves the punch interponents whereby those punch interponents which are in marking position engage and in turn actuate corresponding punches to perforate a telegraph tape. The punches are held in position floatingly and pivotally by tension springs. As the punches are 10 being withdrawn from the tape, the tape is advanced, and due to the freedom of the punches to pivot, they are carried along with the tape until withdrawn therefrom, and immediately upon withdrawal they are snapped back to normal 15 position by their tension springs.

Many features included in the disclosure of the present application are also disclosed and are claimed in the copending application of W. J. Zenner, Serial No. 15,653, filed March 18, 1948, 20 now Patent No. 2,490,608.

Referring to the drawings the punching unit is supported in a pair of side plates 11 of the main frame, shown only fragmentarily in Figs. 1 and 4. The selector cams indicated generally by numeral 12 and the various other operating cams are mounted to sleeves which are rotatable about a shaft 13 which is journaled frictionlessly in a pair of brackets 14 suitably secured to a base (not shown). The shaft 13 is rotated continuously in a clockwise direction by means of a gear 16 which is driven continuously by a suitable source of power (not shown).

A selector cam sleeve 17 is mounted rotatably about the shaft 13 and is integral with a driven 35 member (not shown) of a single revolution selector clutch, the driving drum of which is represented by numeral 18. This clutch whose driving member 18 is secured to the continuously rotating shaft 13 is preferably of the type disclosed in the copending application of A. N. Nilson et al., Serial No. 707,176, filed in the United States Patent Office on November 1, 1946, now Patent No. 2,568,249.

The selector cam sleeve 17 carries the usual 45 series of five selector cams 21, 22, 23, 24 and 25. For the sake of clarity in the drawings only the fifth selector cam 25 is shown in Fig. 1; however, the contour of all of these cams is clear from the timing diagram shown in Fig. 9.

A selector magnet 27 is mounted suitably on the main frame of the reperforator and a selector armature 28 cooperates with the magnet 27. The armature 28 is biased by a spring 29 whereby the left end thereof, Figs. 2 and 3, is held in its lower or spacing position when the magnet 27 is de-energized. Energization of the magnet 27 causes it to pull up the armature 28 to marking position.

A lever 31 is mounted pivotally on a shaft 32 and is urged continuously in a clockwise direction by a spring 33. The lever 31 has a shoulder 34 thereon which is adapted to engage and be blocked by the armature 28 when it is in marking position, but when the armature 28 is in spacing position the lever 31 may be pivoted clockwise by its bias spring 33. A selector clutch trip off lever 36 is mounted pivotally on a shaft 37 suitably secured to the main frame, and carries a pair of pins 38 and 39 which cooperate with the lever 31 in a manner whereby pivotal movement of the lever 31 pivots the selector clutch trip off lever 36. The trip off lever 36 has a foot 41 which cooperates with a clutch lever (not shown) on the driven member of the se- 60

lector clutch. When the trip off lever 36 is pivoted clockwise the foot 41 releases the clutch lever allowing the driven member and selector cam sleeve 17 to be rotated. A selector clutch trip off cam 42 on the selector cam sleeve 17 cooperates with a lug 43 on the trip off lever 36, the low portion 44 of the cam 42 presenting itself opposite the lug 43 upon the completion of each revolution of the selector cam sleeve 17. The cam 42 holds the lever 31 out of engagement with the armature 28 except during the stop and start impulses. The stop impulse of each telegraph signal being a marking impulse, it is apparent that the foot 41 will engage the clutch lever at the end of each signal to stop rotation of the transmitting cam sleeve. The start impulse of each telegraph signal being a spacing impulse, it is also apparent that the transmitting cam sleeve will be released for rotation upon the receipt of each start impulse.

A pair of armature locking levers 46 and 47 are mounted pivotally on a shaft 48 and each is biased clockwise by an individual spring 53. Both of the locking levers have a lug 52 which cooperates with an individual locking cam 49. The locking lever 46 has a stepped shoulder 54 thereon for locking the armature 28 in spacing position and the locking lever 47 has a stepped shoulder 55 for locking the armature 28 in marking position. As is apparent from Fig. 9 the cam 49 has a contoured surface which allows the armature 28 to be held in whichever position it assumes in response to the signal impulses received by the magnet.

The five selector cams 21 through 25 cooperate with a series of five selector levers 61, 62, 63, 64, and 65. Each of the selector levers 61 through 65 is mounted pivotally on a shaft 67 suitably secured to the frame and is yieldable thereon due to the action of individual bars 45, slideable in apertures 58 in a plate 66 secured suitably to the frame, and individual leaf springs 70 which continuously urge the selector levers towards the shaft 67 (Fig. 2). Each of the selector levers is biased in a clockwise direction by an individual tension spring 68. Each of the selector levers has a lug 69 which follows the corresponding selector cam. When the armature 28 moves to marking position in response to one of the signal impulses the locking lever 47 momentarily locks the armature 28 in such marking position during which time the selector lever opposite the low part of the corresponding selector cam moves beneath the armature 28. When the armature 28 is moved to spacing position in response to a signal impulse the locking lever 46 momentarily locks the armature 28 in spacing position. When the armature is thus moved and held in spacing position the selector lever opposite the low part of the corresponding selector cam is blocked by the armature 28 and the lug 69 is prevented from dropping into the low part of such cam.

A series of selector interponents 71, only one of which is shown, have slots 72 therein and are slideable longitudinally. A comb bar 73 secured 65 suitably to the main frame has slots in the transverse edges thereof which position transversely the selector interponents 71. The comb bar 73 fits loosely within the slots 72 of each selector interponent 71 allowing each selector interponent 71 a slight degree of pivotal movement. A shaft 74 suitably secured to the main frame limits the clockwise pivotal movement of the selector interponents 71 and a series of springs 76 secured 70 suitably to the main frame continuously urges

the selector interponents 71 in a clockwise direction.

Each selector interponent 71 cooperates with a corresponding one of the selector levers 61 through 65 whereby a foot 77 on each selector interponent 71 remains on top of the corresponding selector lever whenever a spacing impulse controls such selector lever and drops behind the selector lever when a marking impulse controls it. Referring to the selector cam 25, selector lever 65 and the selector interponent 71 in the fifth position, when the foot 77 drops behind the selector lever 65 in the manner described, subsequent rotation of the cam sleeve 17 brings an extra high portion 78 of the selector cam 25 against the lug 69 which pivots the selector lever 65 counterclockwise thereby moving the selector interponent 71 to the left to set a corresponding punch interponent 85 of a series of punch interponents 81, 82, 83, 84 and 85.

A latch bail 87 secured pivotally to the main frame at points 88 and biased in a clockwise direction by a spring 89 is adapted to latch a tooth 99 on any of the punch interponents 81 through 85 moved by the selector interponents 71 in the above-described manner. A bell crank lever 91 secured pivotally to the main frame by a bolt 92 has a cam follower 93 which follows a punch interponent release cam 94. The follower 93 is continuously urged against the cam 94 due to the action of a tension spring 96 suitably secured to the main frame. An upturned end portion 97 of the bell crank lever 91 cooperates with a lug 98 on the latch bail 87 to disengage the latch bail 87 from the punch interponents 81 through 85 when the high part of the cam 94 is opposite the follower 93.

When all of the punch interponents 81 through 85 have been set due to the action of the extra high portions on the selector cams 21 through 25, a bail 56 is actuated to disengage the selector interponents 71 from the selector levers 61 through 65. The bail 56 consists of an L-shaped member pivoted to the main frame by a bolt 57 and is continuously urged in a counterclockwise direction by a spring 58. The bail 56 has a cam follower 59 thereon adapted to ride a cam 60. As the cam 60 rotates, the high portion thereof, upon engagement with the cam follower 59, pivots the bail 56 against the action of the spring 58 to erase any selection existing in the set of selector interponents 71 by moving them all to spacing position preparatory to the next selection to be set up therein.

Each of the punch interponents 81 through 85 is supported in a punch bail 101. A pair of comb bars 102 and 103, integral parts of the punch bail 101, position transversely the punch interponents and allow them to slide longitudinally in the punch bail 101. A set of tension springs 106 secured suitably to the punch bail 101 urge the punch interponents 81 through 85 to the right or spacing position. The punch bail 101 is supported pivotally in the side plates 11 by a pair of pivot bolts 104 and is actuated pivotally about bolts 104 by a toggle mechanism indicated generally by reference numeral 107.

A punch clutch actuating cam 108 mounted on the selector cam sleeve 17 controls a single revolution punch clutch 109. The clutch 109 is preferably of the same type as the selector clutch, the driving drum of which is indicated by numeral 18. The clutch 109 has a driving drum 111 which is secured to the continuously rotating shaft 13 and cooperates with a driven member

112 secured to a sleeve 113 freely rotatable on the shaft 13. A punch clutch trip off lever 114, secured to a shaft 116 mounted pivotally in the side plates 11, cooperates with a clutch lever 117 to trip off the punch clutch 109. A cam follower lever 118 secured to the shaft 116 is continuously urged in a counterclockwise direction by a spring 119 whereby a follower 121 is held in engagement with the punch clutch actuating cam 108. When the high portion of the cam 108 presents itself to the follower 121 the shaft 116 is rotated clockwise sufficiently to pivot the trip off lever 114 from engagement with the clutch lever 117 thereby releasing the clutch 109 for rotation. It is, therefore, clear that the punch clutch 109 is only tripped off when the selector clutch has been tripped off previously.

A punch eccentric 122 is secured to the sleeve 113 and as the punch eccentric 122 rotates it substantially reciprocates a lever 123. The lever 123 is secured pivotally by a bolt 124 to one arm of a U-shaped lever 126 and is adapted to oscillate pivotally the U-shaped lever 126 about a bolt 127 secured rigidly to the reperforator frame. The other arm of the U-shaped lever 126 is connected pivotally to a link 128 by a bolt 129 whereby reciprocation of the lever 123 is transferred to the link 128. The link 128 is secured to a shaft 131 which actuates the toggle mechanism 107.

A beam 132 is mounted rotatably between the side plates 11 on a shaft 133. A U-shaped lever 134 secured to the beam 132 has a pair of arms 136 and 137 which are secured pivotally to the shaft 131. Adjacent the arms 136 and 137 are a pair of levers 138 and 139 also pivoted to the shaft 131. The levers 138 and 139 are secured pivotally at the opposite ends thereof to the punch bail 101 by a pair of bolts 141. As the link 128 moves to the left straightening the toggle mechanism consisting of the arms 136 and 137 and the levers 138 and 139, the punch bail 101 is raised and conversely as the link 128 is moved to the right the toggle mechanism breaks and the punch bail 101 is lowered.

A punch block 142 is supported rigidly between the side plates 11 and has a series of open faced slots 143 within which a series of punches 144 are reciprocable. A comb bar 146 supported between the side plates 11 serves to guide the punches 144 and acts as a stop for the punches, engaging a shoulder 147 on each punch 144 as the punch is lowered. A die plate 148 is bolted to the punch block 142 and has a series of open faced slots (not shown) within which the punches 144 extend during the upward movement thereof. Each punch 144 is held within its slot 143 by a spring 149 which is secured to a bar 151 suitably mounted between the side plates 11. The punches 144 are therefore floatingly mounted in the punch block 142.

A shaft 154 mounted between the side plates 11 supports a rotatable sleeve 155. A tape feed hole punch wheel 156 is secured to the sleeve 155, and a series of feed hole punches 157 formed on the periphery of the wheel 156 mesh with die holes 158 spaced uniformly around the periphery of a die wheel 159 freely rotatable on a shaft 160. Rotation is imparted to the punch wheel 156 and die wheel 159 by means of a ratchet wheel 161 secured to the sleeve 155. A tape guide wheel 162 having a shoulder 163 around the periphery thereof is also mounted on the sleeve 155. A tape feed guide 164 guides a tape 166 into position where it is engaged by the feed

hole punch wheel 156 and the tape guide wheel 162 and as the feed hole punch wheel 156 and the die wheel 159 mesh with the tape 166 therebetween a series of uniformly spaced feed holes are punched in the tape 166. The correct transverse position of the feed holes in the tape 166 is maintained by the tape guide wheel 162 as the edge of the tape 166 abuts the shoulder 163. The tape is then advanced through a slot (not shown) between the punch block 142 and the die 10 plate 148.

The ratchet wheel 161 is rotated by means of a pawl 167. The pawl 167 is secured pivotally by a bolt 168 to an extended portion 169 of the arm 136 and is biased in a counterclockwise direction by a spring 171 suitably secured to the main frame. A detent lever 172 is secured pivotally to the side plate 11 by a bolt 173 and is biased in a counterclockwise direction by a spring 174. The detent lever 172 carries a detent roller 176 which engages the ratchet wheel 161 between the teeth on the periphery thereof to prevent backward rotation of the ratchet wheel 161 while the feed pawl 167 is being returned preparatory to making another stroke. As the 20 toggle mechanism 107 is straightened to actuate the punch bail 101, the extended portion 169 on the arm 136 is pivoted counterclockwise which pulls down the feed pawl 167 causing it to slip over one of the teeth on the ratchet wheel 161 and thereafter as the toggle 107 breaks, the feed pawl 167 is moved up to step the ratchet wheel 161, after which it is held in stepped position by the detent roller 176.

When the punch bail 101 is raised extended portions 177 on each of the punch interponents 81 through 85 which have been previously moved to marking position engage shoulders 178 on corresponding punches 144 to raise these punches forcing the cutting edges thereof through the tape 166. Thereafter as the punch bail 101 is lowered the tape 166 is advanced and the punches 144 which were raised to tape piercing position are carried along and pivoted counterclockwise to the dotted position 179 shown in Fig. 2. As the punch bail 101 is lowered the extended portion 177 on each of the selected punch interponents 81 through 85 engages a foot 181 on each punch 144 to withdraw the punches 144. The perforations thus left in the tape 166 after the punching operations are of the well known chadless type wherein the portions of the tape punched out remain hinged to the tape giving the appearance of trap doors. Fig. 5 shows an example of the tape perforated by the above described reperforator.

A brief description of the operation of the invention follows. The selector magnet 27 is energized and de-energized in accordance with the signals received thereby from a distant transmitter (not shown). The armature 28 is accordingly pulled up when the magnet 27 is energized and allowed to fall due to the urging of the spring 29 when de-energized. Normally when no signals are being received the magnet 27 is energized as the transmitter sending the signals is in its stop position, a marking position. The armature 28, being pulled up, blocks the shoulder 34 to prevent pivotal movement of the selector clutch trip off lever 36 thus preventing rotation of the selector cam sleeve 17. When a start impulse is received, being a spacing impulse, the magnet 27 is de-energized which allows the armature 28 to move to spacing position. At this time, the low portion of the cam 75

44 being opposite the lug 43 and the shoulder 34 being unblocked, the selector clutch trip off lever 36 pivots clockwise to trip off the selector clutch.

5 After the start signal is received by the selector magnet 27, five permuted marking or spacing impulses are received in timed relation to the presentation of the low portions of the selector cams 21 through 25 to the cooperating lug followers 69 on the selector levers 61 through 65. Each marking or spacing impulse is received shortly prior to the presentation of the low part of the selector cams to the lug followers 69 and is received just prior to the presentation of one of the low portions of the locking cam 49. This allows the armature 28 to respond to the impulse and to be thereafter locked by the locking lever 46 if the impulse is a spacing impulse and by the locking lever 47 if it is a marking impulse. The armature 28 being locked in this manner assures that it will be in the correct position to properly control the setting of the selector levers 61 through 65. The locking lever 46 or 47 whose follower 52 has entered one of the low portions of the locking cam 49 is urged counterclockwise (Fig. 2) after each signal impulse is received by the proper selector levers 61 through 65 in order to allow the armature 28 to respond to the subsequent impulse received by the magnet 27.

The selector interponents 71 cooperating with the selector levers which have been moved to marking position drop behind the corresponding selector levers, and the selector interponents 71 cooperating with selector levers which are in spacing position remain on top of the corresponding selector levers. When the selection of the selector levers has been made, extra high portions of the selector cams 21 through 25 move the selector levers counterclockwise beyond the normal positions thereof. When the selector levers are moved in this manner, the selector interponents 71 which have dropped behind the selector levers are moved further to the left and those selector interponents 71 which are positioned on top of their corresponding selector levers remain in the rightward position thereof (Fig. 2), the selector levers merely sliding beneath the feet 77.

45 As the selector interponents 71 move to the left in this manner they engage and push corresponding punch interponents 81 through 85 to the left whereby the teeth 99 on the punch interponents so moved slip beneath and are thereafter latched by the latch bail 87. The punch interponents 81 through 85 having been latched in marking position, the selector interponents 71 return to the right due to the action of the springs 76 when the bail 56 is actuated by the cam 60. Shortly thereafter the selector interponent release bail 56 is pivoted clockwise by the cam 60 to lift all of the selector interponents 71 previously moved to marking position, leaving them on top of the selector levers, thus erasing the selection existing therein. By this time the selector cam sleeve 17 has commenced a second revolution and the signal received during the first revolution thereof is stored in the punch interponents 81 through 85.

70 The extended portions 177 on the punch interponents 81 through 85 which have been moved to the left (Fig. 2) or marking position are in positions for actuating their respective corresponding punches 144 when the punch interponents are raised. The toggle mechanism 107 for raising the punch bail 101 commences

straightening at substantially the same time that the punch interponents are selectively positioned by the selector interponents 71, and is completely straightened at a time between the selection of the first and second impulses of the next succeeding signal. During the period when the toggle 107 is straightening, the feed pawl 167 is being backed up and the feed hole punch wheel 156 is rendered stationary by the detent 172 cooperating with the ratchet wheel 161.

The tape 166 being stationary during the upward movement of the punch bail 101, the selected punches 144 are engaged on their shoulders 178 by the extended portions 177 of the punch interponents and the punches 144 are therefore raised vertically, the springs 149 holding the punches 144 within the slots 143 in the punch block 142. The punches 144 pierce the tape 166 leaving the chad attached thereto. Upon straightening of the toggle 107, the punches 144 attain their uppermost position. Thereafter, as breaking of the toggle 107 continues, the pawl 167 engages a tooth in the ratchet wheel 161 to advance the feed hole punch wheel 156 a step. Such movement of the punch wheel 156 causes another of the punches 157 to enter one of the die holes 158 in the die wheel to punch another feed hole in the tape 166. The feed holes thus punched, like the code holes punched by the punches 144, have the chad attached to the tape. Besides punching the feed holes in the tape 166, the feed hole punch wheel 156 also advances the tape 166. The tape 166 is advanced while the punches 144 are being withdrawn therefrom and the punches 144 are therefore carried along with the tape 166 to the dotted position thereof represented by numeral 179. As the bail 101 is lowered due to the breaking of the toggle 107, the extended portions 177 of the punch interponents engage the feet 181 of the punches 144 to lower the punches from the tape 166. The punches 144, upon withdrawal from the tape 166 are immediately snapped back into position in the guide slots 143.

Very shortly after the tape feeding is completed and the punches 144 are completely withdrawn the high portion on the punch interponent release cam 94 presents itself to the cam follower 93 pivoting the bell crank 91 clockwise to raise the latch bail 87 from engagement with the teeth 99 on the punch interponents. The springs 106 on each of the punch interponents then are free to move their punch interponents to the right or unselected position. Thereafter the entire punching mechanism is ready for the next selection.

A modification of the invention is shown in Fig. 6. In the following description of this embodiment those parts which have reference numerals the same as parts already described are identical therewith. Only those parts are shown and described which are considered necessary to differentiate from the first embodiment.

The shaft 13 has the selector cam sleeve 17 therearound which is under control of a selector clutch (not shown in Fig. 6). The selector cams are represented by the fifth selector cam 25 and the selector levers are represented by the fifth selector lever 65. The selector levers are all mounted pivotally on the shaft 67 and are spring biased clockwise about the shaft 67 by individual springs 68. When a marking impulse is received the armature 28 is pulled up (as illustrated) by the magnet and the selector lever 65 is allowed to be biased in a clockwise direction when the lug 69 engages the low part of the cam 25.

A set of five selector interponents, represented by the fifth selector interponents 201, are pivotal on a shaft 202, and all are spring biased clockwise about the shaft 202 by springs 203 secured to the vertical arms 204. The shaft 202 is positioned within a cam slot 206 in each selector interponent 201. Each of the cam slots 206 has an upper horizontal portion 207 which allows the selector interponent 201 to slide horizontally a slight amount. In normal unselected position the selector interponents 201 are resting with the right extremities thereof on top of the selector levers 65. When any of the selector levers 65 become selected they move clockwise sufficiently to allow the rightward extremities of the selector interponents 201 to slip therebehind and come to rest momentarily on the bail 56. Thereafter, as the selector cams 25 continue rotating, the extra high portions 78 thereof engage the lugs 69 to pivot the selector levers 65 counterclockwise. The upper portion of the selector levers 65 which have been moved in response to a spacing impulse slide beneath the rightward extremities of the unselected selector interponents 201 and the selector levers 65 which have been moved in response to a marking impulse move the corresponding selected selector interponents 201 to the left, during which movement the left ends of the selector interponents are raised due to the camming action of the shaft 202 within the slots 206. Raising the selector interponents 201 in this manner causes a tooth 208 on each selected selector interponent 201 to become disengaged from a cooperating tooth 209 on each corresponding punch interponent 211.

There are five punch interponents 211 which are mounted slidably within the punch bail 101 by means of a pair of comb bars 212 and 213. Each of the punch interponents 211 has a vertical arm 214 to which is secured a spring 215 for biasing the punch interponents 211 to the left. Therefore when the teeth 208 on the selector interponents 201 become disengaged from the corresponding teeth 209 the punch interponents 211 are moved to the left by the springs 215. When the punch interponents 211 are moved in this manner the extended portions 177 thereon are positioned suitably for actuating the corresponding punches 144 as the toggle 107 straightens.

A cam 217 secured to the punch clutch sleeve 113 cooperates with a follower 218 of a lever 219 mounted pivotally at 221. A link 222 is secured pivotally at one end thereof to the lever 219 by a pivot bolt 223 and the other end of said link 222 is secured pivotally to a lever 224 by a pivot bolt 226. The lever 224 is mounted pivotally by a bolt 227 and carries a bail 228. The two levers 219 and 224 are urged in a counterclockwise direction by a spring 229. When the high portion of the cam 217 engages the follower 218 the two levers 219 and 224 are pivoted clockwise and the bail 228 is moved to the right. The bail 228 engages a lug 231 on each of the previously selected punch interponents 211 and moves the punch interponents to the right where they are latched by the teeth 208 and 209. The teeth 208 and 209 each have cam surfaces thereon and the punch interponent 211 can move vertically sufficiently in the slots in the comb bar 213 so that the tooth 209 can slip past the tooth 208.

Shortly after the selection set up in the selector interponents 201 is transferred to the punch interponents 211 the bail 56 is raised in

11

the manner hereinbefore described to strip the selector interponents 201 from behind the selector levers 65 and thereby erase the selection existing in the selector interponents 201. A subsequent revolution of the selector cam assembly produces a new selection in the selector interponents 201. Just prior to a complete break of the toggle 107 to the position thereof shown in Fig. 6 the high portion of the cam 211 engages the follower 218 causing the punch interponents 211 to be moved to the right and latched in unselected position. Thereafter the follower 218 rides off the high portion of the cam 211 and the spring 229 causes the bail 228 to be withdrawn from the teeth 231. The new selection, having been set up in the selector levers 65 and selector interponents 201, is then transferred to the punch interponents 211 in the manner previously described.

In this modification of the invention a set of pivoted punches 144 are movable within a pivoted punch block 241 (Fig. 8). A punch block frame 242 is secured pivotally to the side plates 11 at pivot points 243 and has the pivoted punch block 241 secured thereto. The horizontal portion of the punch block frame 242 serves as a die block 240. Horizontal extensions 244 on the punch block frame 242 have slots 246 (Fig. 6) in the extremities thereof within which a pair of studs 247 protrude. When the punch bail 101 is raised, due to the straightening of the toggle 107, the studs 247 within the slots 246 raise the horizontal extensions 244 of the punch block frame 242 pivoting the punch block frame 242 counterclockwise.

A pair of tape feed pawls 248 and 249 are secured pivotally to the punch bail 101 by a bolt 251 and are biased towards a feed ratchet wheel 252 by a spring 253. The feed pawl 249 is adapted to engage a tooth in the ratchet wheel 252 to rotatably advance the wheel 252 clockwise (Fig. 7) during the down stroke of the punch bail 101 and the feed pawl 248 engages a tooth on the ratchet wheel 252 to advance the wheel 252 during the up stroke of the punch bail 101. The feed ratchet wheel 252 is secured to the sleeve 155 to which is also secured the tape feed hole punch wheel 156. The feed hole punch wheel 156 cooperates with the feed hole die wheel 159 to punch feed holes in a tape advancing therebetween in the manner hereinbefore described.

Assuming that a selection has been set up in the punch interponents 211 the operation of the pivoted punch block is as follows. As the toggle 107 straightens, the punches 144 corresponding to those punch interponents 211 which have moved to the left (Fig. 6) are raised to perforate the tape 166 (not shown in Fig. 6) as the tape moves through a tape slot 254. At the same time the punch block 241 is pivoted forward (Fig. 7) carrying with it the punches 144. Also at the same time the feed pawl 248 engages and advances the ratchet wheel clockwise to advance the tape an amount equal to the distance the punch block 241 is pivoted. On the return stroke of the punch bail 101, as the toggle 107 breaks, the pawl 249 advances the tape further and the punch block moves back to the position shown in Fig. 7. The punches 144, being within the perforations in the tape at the start of the return stroke of the punch bail 101, are carried along with the tape and pivot relative to the punch block 241 until they are withdrawn from the tape, whereupon they snap back into the normal position thereof as shown in Figs. 6 and

12

7. The holes perforated in the tape, like those perforated by the reperforator comprising the first embodiment of the invention, are of the chadless type.

5 Following is a description of a backspace mechanism for the reperforator having pivoted punches and a pivoted punch block. A ratchet wheel 261 is secured to the sleeve 155 and normally rotates therewith. A manually operable plate 262 has a bent over top portion 263 by means of which the plate 262 may be depressed. A pin 264 secured to the side plate 11 protrudes through a longitudinal slot 266 to guide the plate 262 when it is depressed. A wide slot 267 in the plate 262 surrounds the sleeve 155 and prevents the plate 262 from moving laterally. A pin 268 secured to the plate 262 has a spring 269 attached thereto which spring 269 is also attached to the pin 264 and continuously urges 10 the plate 262 upwards. A pawl 271 is secured pivotally to the plate 262 by a bolt 272 and has a depending arm 273 having a cam surface 274 thereon which cam surface 274 cooperates with an adjustable eccentric 276 secured to the side frame 11. The pawl 271 also has a horizontal arm 277 which carries a spring 278 secured at its other end to a horizontal arm 279 on the plate 262. The spring 278 tends to urge the pawl 271 in a clockwise direction towards the ratchet wheel 261 but the pawl 271 is held disengaged 15 from the ratchet 261 normally due to engagement of the cam surface 274 on the depending arm 273 with the eccentric 276. Therefore, during normal operation the ratchet wheel 261 is free to rotate as the sleeve 155 rotates.

20 The plate 262 carries a pin 281 substantially opposite the pin 268 which is adapted to operate with the lower portions of the pawls 248 and 249 when the plate 262 is depressed to cam said pawls 248 and 249 from engagement with the ratchet wheel 252. When the plate 262 is depressed the pawls 248 and 249 are cammed from engagement with the ratchet wheel 252 after which the cam surface 274 overrides the eccentric 276 allowing the spring 278 to urge the pawl 271 against the ratchet wheel 261. Upon further depression of the plate 262 the pawl 271 engages a tooth on the ratchet wheel 261 and moves the wheel 261 counterclockwise, thus backing up the tape (not shown) over the feed hole punch wheel 156.

25 A chad flattener 282 has five wedge-shaped lugs 283 positioned on the under side thereof which are aligned with the five punches 144 positioned in the punch block 241. The chad flattener 282 is formed with a pin 284 integral therewith which pin 284 is slidable longitudinally in a hole 286 through the punch block 241. A pin 287 secured to the punch block frame 242 also helps to position the chad flattener 282 by extending through a hole (not shown) in the chad flattener 282. A horizontal arm 288 has a tension spring 289 secured thereto which spring 289 is secured at its other end to the chad flattener 282. A rod 291 is positioned within the spring 289 to maintain the chad flattener 282 out of engagement with the tape at all times except when a backspacing operation is in progress.

30 In the operation of the chad flattener 282 during a backspace operation the chad flattener 282 is lowered during the first part of the depression of the plate 262 due to the urging of the spring 289. When the chad flattener 282 is lowered in this way one of the wedge-shaped lugs 35 283 is lowered above each row of perforations

in the tape into the slots 292 in the die block 240. Further depression of the plate 262 merely stretches the spring 289 and the lugs 283 are held in their lowered position until the plate 262 is released and pulled up by the spring 269 until the rod 289 lifts the chad flattener 282.

The lids in the tape as it is being perforated are hinged at the forward end thereof so that when the tape is backspaced the tendency is for the lids to turn upwards. However, when the wedges 283 are brought downwards against the tape the lids in the tape are directed downwards into the apertures in the tape so that when the tape is backed up by the backspace mechanism the lids will not interfere.

In Fig. 10 there are shown several different shapes of punches 301, 302, 303, and 304 all of which may be used with the invention. The punch indicated by reference numeral 301 produces a chadless tape with apertures having round backs. The punch 302 produces a square aperture in the tape like that shown in Fig. 5. The punch 303 produces a hole substantially round except for a narrow lid. The punch 304 merely pierces the tape.

Figs. 11, 12, 13, and 14 show various types of tape feed hole punch wheels and die wheels. In Fig. 11 a feed wheel 306 has round feed hole punches 307 which mesh with elliptically shaped die holes 308 in a die wheel 309. In Fig. 12 a feed wheel 311 has square feed hole punches 312 adapted to enter a peripheral groove 313 in a die wheel 314. Fig. 13 shows a feed wheel 316 having square feed hole punches 317 which mesh with substantially square holes 318 in a die wheel 319. Fig. 14 shows a feed wheel 321 having needle pointed punches 322 which mesh with substantially round holes 323 in a die wheel 324.

Various changes and modifications may be made in the invention without departing from the scope thereof.

What is claimed is:

1. In an apparatus for perforating a control form, a plurality of pivotally mounted punches, a die block having a plurality of open faced slots for cooperating with said punches to perforate the control form, means for normally holding the punches in a nonperforating position, toggle means for moving said punches into said open faced slots to thereby perforate the control form, said toggle means further functioning to withdraw said punches from the control form, and a rotary punch means operated by the breaking of the toggle for punching and advancing the control form while said punches are being withdrawn therefrom, whereby said punches are pivoted against the effect of the holding means by the advancing control form while being moved out of said open faced slots in said die block.

2. In an apparatus for perforating a control form, a plurality of pivotally mounted punches for perforating the control form, a pivotally mounted punch block normally positioned in nonperforating position and having a plurality of open faced slots for guiding said punches, means for normally holding the punches within the slots in nonperforating position, means for pivoting said punch block into perforating position and for returning said punch block to nonperforating position, means for actuating said punches, whereby said punches are moved to perforate the control form and thereafter returned to normal position, and means for advancing the control form during the pivotal

movement and return to nonperforating position of said punch block, said punches being moved to perforate the control form during the pivotal movement of said punch block and said punches being returned by the holding means to normal position during the return of said punch block to nonperforating position, whereby said punches are moved pivotally against the effect of the holding means within said open faced slots in said punch block by the advancing control form during the return of said punches to normal position.

3. In an apparatus for perforating a control form, a pivotally mounted punch, a pivotally mounted punch block normally positioned in non-perforating position and having an open faced slot for guiding said punch, means for normally retaining the punch within the open faced slot in nonperforating position, a die block secured to said pivotally mounted punch block and having an open faced slot for cooperation with said punch to perforate the control form, means for pivoting said punch and die blocks into perforating position and for returning said punch and die blocks to nonperforating position, means for actuating said punch, whereby said punch is moved within said open faced slots in said punch and die blocks to perforate the control form and thereafter returned to normal position, and means for advancing the control form during the pivotal movement and return to nonperforating position of said punch and die blocks, said punch being moved to perforate the control form during the pivotal movement of said punch and die blocks and said punch being returned by the retaining means to normal position during the return of said punch and die blocks to nonperforating position, whereby said punch is moved pivotally against the effect of the retaining means within said open faced slots in said punch and die blocks by the advancing control form during the return of said punch to normal position.

4. In an apparatus for perforating a control form, a plurality of pivotally mounted punches, a pivotally mounted punch block normally positioned in nonperforating position and having a plurality of open faced slots for guiding said punches, resilient means for normally retaining the punches within the slots in nonperforating position, a die block secured to said pivotally mounted punch block and having a plurality of open faced slots for cooperating with said punches to perforate the control form, means for pivoting said punch and die blocks into perforating position and for returning said punch and die blocks to nonperforating position, means for actuating said punches, whereby said punches are moved within said open faced slots in said punch and die blocks to perforate the control form and thereafter returned to normal position, and means for advancing the control form during the pivotal movement and return to nonperforating position of said punch and die blocks, said punches being moved to perforate the control form during the pivotal movement of said punch and die blocks and said punches being returned by the resilient means to normal position during the return of said punch and die blocks to nonperforating position, whereby said punches are moved pivotally against the effect of the resilient means within said open faced slots in said punch and die blocks by the advancing control form during the return of said punches to normal position.

5. In an apparatus for perforating a control form, a movable punch block having a plurality of open faced slots therein, a punch positioned within each of said slots, means for retaining said punches against the rear walls of said slots, means for moving said punch block into and out of perforating position, means for simultaneously moving the punches into and out of perforating position during the movement of the punch block into and out of perforating position, and means for advancing the control form during the movement of the punch block into and out of perforating position, said punches being pivoted against the effect of the retaining means by the advance of the control form during a portion of the return movement of the punch block to the nonperforating position.

6. In an apparatus for perforating a control form, a pivotally mounted punch block having a plurality of slots formed therein, a punch positioned within each of the slots, means for urging the punches against the rear walls of the slots, engaging means for moving the punches and simultaneously pivoting the punch block into perforating position, means for advancing the control form during the punching operation in the direction of the pivotal movement of the punch block, means for subsequently withdrawing the punch block and punch from the perforating position, and means for further advancing the control form in the aforementioned direction during the return movement of the punches and punch block to the nonperforating position.

7. In an apparatus for perforating a control form, a pivotally mounted punch block having a plurality of slots formed therein, a punch positioned within each of the slots, means for normally retaining the punches in a nonperforating position against the rear walls of said slots, means for engaging the punches, means interconnecting the punch block and the engaging means, a toggle connected to said engaging means and normally broken to maintain the punches and punch block in a nonperforating position, means for straightening the toggle to move the punches and punch block into perforating position, and means for simultaneously advancing the control form upon movement of the punch block.

8. In an apparatus for perforating a control form, a punch block having a plurality of slots formed therein, a punch positioned within each of said slots, means for urging said punches against the rear walls of said slots, means for engaging the punches to move them into perforating position, a normally broken toggle connected to the engaging means for maintaining the punches in a nonperforating position, means for straightening and breaking the toggle to move the engaging means and punches into and out of the perforating position, a rotary punch, a ratchet for advancing the rotary punch to advance the tape, a pawl operated by the breaking of the toggle for engaging and advancing the ratchet to advance the rotary punch to advance the control form during the return of the punches to the nonperforating position.

9. In an apparatus for perforating a control form, a plurality of first punches, means for normally retaining the first punches in a nonperforating position, means for moving the first punches into and out of a perforating position, a rotary punch, means actuated by the first punch moving means during the movement of the first punches into and out of the perforated position for advancing the rotary punch to advance the control form unidirectionally, control form backspacing means for moving the rotary punch in a direction opposite to that of the advancing means, and means for disengaging the rotary punch advancing means upon actuation of the backspacing means.

10. In an apparatus for perforating a control form, a plurality of punches adapted to perforate lidded apertures in the control form, means for moving the punches into and out of a perforating position, means for advancing the control form subsequent to each perforating operation, a mechanism for disengaging said control form advancing means and moving the control form backwards, and means rendered effective upon operation of said mechanism for guiding the lids formed during the perforating operation to facilitate the backward movement of the control form.

11. In an apparatus for perforating a control form, a plurality of pivotally mounted punches, means for moving the punches into and out of position to perforate the control form, means for urging said punches against pivoted movement during said movement of the punches into and out of perforating position, a rotary punch normally engaging said control form, means operated by the said moving means subsequent to a perforating operation for rotating the rotary punch to perforate and advance the tape, said rotary punch causing the control form to engage and pivot the punches against the effect of the urging means, a mechanism for disengaging the means for rotating the rotary punch, said mechanism including means for rotating the rotary punch to backspace the control form.
